FOUNTAIN APPLICATOR

Oliver J. Brown, Cincinnati, Ohio

Application November 29, 1938, Serial No. 242,971

3 Claims. (Cl. 15—133)

This invention relates to a manicure implement and is especially directed to a fountain applicator for nail polish or the like.

An object of the invention is to provide a novel and an effective and efficient means for applying nail polish which is at present applied by means of a brush dipped into a bottle containing said polish.

Another object of the invention is to provide a simplified brush head having novel structural features and also means thereon for removably positioning a brush.

A further object of the invention is to provide an improved bulb for the discharge of a definite, limited quantity of polish.

Another object of the invention is to provide a means of manipulating the implement by means of a suitable holder.

Other objects resulting from particular combinations of the above features will be apparent from the following specification and drawing, in which:

Fig. 1 is a top plan view of my nail polish applicator.

Fig. 2 is a cross-sectional view taken on line 2—2 of Fig. 1.

Fig. 3 is a cross-sectional view taken on line 3—3 of Fig. 2.

Fig. 4 is a cross-sectional view taken on line 30 4—4 of Fig. 2.

Fig. 5 is a cross-sectional, detail view of the ball detent means of the implement.

Fig. 6 is an enlarged perspective view of the brush of the device.

The embodiment of my invention consists of a cylindrical barrel 10, preferably made of glass for containing the liquid nail polish. One end of the barrel is provided with exterior screw threads 11 adapted to engage interior threads provided for removable closure cap 12. The other end of the barrel is fitted with a brush head generally indicated as 13 which may be frictionally held or threaded to the interior surface of the barrel. The brush head has an integral reduced, elongated portion 14 at the outer extremity thereof and is also formed with a transverse shoulder 15 which is disposed at right angles to the direction of extension of the head. An elongated discharge opening 16 is formed at the outer end of the reduced portion and communicates with the interior of the barrel by means of a passageway 17 formed in the head. It will be noted that the discharge opening and the passageway are disposed in a longitudinal alignment substantially centrally of the head interior and that

the discharge opening terminates a substantial distance from the shoulder 15, thereby providing a surface 18 adjacent and at right angles to said shoulder portion. A removable brush 19 comprising a metal band 20 provided with a slot 21 and a number of bristles 22 bound together by said band is disposed adjacent the discharge opening 16 and extends beyond the outer end of the head 13. Means for positioning the brush comprises a flexible pin 23 which is embedded in the shoulder portion and is positioned therein in such manner as to receive the slot 21 formed in the band 20 to rigidly clamp said band between the pin and the surface 18. The brush is thereby rigidly fastened to the head and may be removed from time to time for replacement or cleaning. The end of the barrel to which the head is positioned is provided with exterior threads 24 to which a cap 25, indicated in dotted lines in Fig. 1, may be threaded to protect said head when the implement is not in use.

The barrel is provided with a means for introducing a definite and limited quantity of polish through the discharge opening 16 and on to the brush 19 which comprises an integral flange 26 formed on said barrel adjacent the brush head. An elastic bulb 27 has a rounded portion extending from the circular rim 28 which is accessible to the thumb of the user when cap 29 is removed. The bulb is fastened to the interior surface of the rim by means of an annular shoulder 30 formed on said bulb which fits into an annular offset formed about the interior wall of the rim.

A holder 31 having an elliptical shape both in longitudinal and transverse cross-section is provided for the implement and has a circular, longitudinal groove 32 formed therein for receiving the barrel 10 of said implement. Means for removably holding the barrel within the groove comprises a ball detent 33 countersunk in the holder with ball 34 resiliently protruding from the surface of the groove.

What is claimed is:

1. A nail polish applicator comprising a barrel 45 for containing liquid polish, a brush head fitted to one end of the barrel and having a reduced, elongated portion at the outer extremity thereof, a shoulder located transversely of and adjacent the reduced portion, an elongated discharge opening formed in said reduced portion, and a passageway 50 formed in the head and communicating with the contents of the barrel and the discharge opening, a bristle tuft disposed adjacent the discharge opening and extending beyond the head, a slotted 55

bristle-retaining band for the bristle tuft, a flexible pin embedded in the shoulder, and adapted to engage said slotted band to hold the bristle tuft in position, bulb pump means on the barrel, and a holder element for the barrel.

2. A nail polish applicator comprising a barrel, a brush head fitted to one end of the barrel and having a reduced, elongated portion at its outer end, a shoulder located transversely of and adjacent the inner end of the reduced portion, an elongated discharge opening formed longitudinally in the reduced portion, a passage formed in the head and communicating with the interior of the barrel and the discharge opening, a slotted retaining band disposed adjacent the shoulder, a number of brush bristles bound by the band and located adjacent the discharge opening and extending beyond the reduced portion, and a flexible pin embedded in the shoulder and adapted to

engage the slotted band to removably hold the brush in position.

3. A nail polish applicator comprising a barrel, a brush head fitted to one end of the barrel and having a reduced, elongated portion at its outer end, a shoulder located transversely of and adjacent the inner end of the reduced portion, an elongated discharge opening formed longitudinally in the reduced portion, a passage formed in the head and communicating with the interior of the barrel and the discharge opening, a slotted retaining band disposed adjacent the shoulder, a number of brush bristles bound by the band and located adjacent the discharge opening and extending beyond the reduced portion, and a flexible pin embedded in the shoulder and adapted to engage the slotted band to hold the brush in position.
